UNITED STATES PATENT OFFICE.

RICHARD H. FESPERMAN, OF TULSA, INDIAN TERRITORY.

HINGE FOR BARREL-COVERS.

SPECIFICATION forming part of Letters Patent No. 744,737, dated November 24, 1903.

Application filed August 3, 1903. Serial No. 168,108. (No model.)

To all whom it may concern:

Be it known that I, RICHARD H. FESPERMAN, a citizen of the United States, residing at Tulsa, in the Creek Nation, Indian Territory, have invented a new and useful Hinge for Barrel-Covers, of which the following is a specification.

This invention relates to means for detachably and movably connecting covers to barrels, boxes, and like receptacles, and has for its object to simplify and improve devices of this character and produce a device simple in construction, quickly and easily applied, and which will be concealed when the cover is closed; and the invention consists in certain novel features of construction, as herein-after shown and described, and specified in the claims.

In the drawings illustrative of the invention, in which corresponding parts are denoted by like designating characters, Figure 1 is a sectional view of a portion of a receptacle and its cover with the improved device applied. Fig. 2 is a perspective view of the improved device detached.

The device may be applied to barrels, boxes of various kinds and similar receptacles, but for the purpose of illustration is shown applied to a barrel and its removable cover, to which it is more particularly adapted; but it will be understood that I do not wish to be limited in the use of the device to any specific form of receptacle or to receptacles employed for any specific purpose, but reserve the right to its use for any purpose or upon any structure to which it is adapted.

The improved device is intended more particularly for use in stores and warehouses upon barrels, boxes, and similar receptacles to which access is frequently required and the contents of which it is necessary to protect, and it consists in a U-shaped clip member 10, having a set-screw 11 engaging one leg and with spaced perforated ears 12 13 extending from the other leg, as shown. The clip member is adapted to fit over the chime of a barrel 14 or over the edge of a box or like receptacle, with the ears on the interior thereof and below the upper edge. Hinged at one end by a pintle 15 between the ears 12 13 is an arm 16, the free end of the arm carrying a plate 20, hinged thereto by a pin-

plate 17, which passes through ears 18 19, extending from the plate 20, said plate being adapted for attachment, as by screws, to the under side of the cover member 21 of the receptacle, as shown. By this simple means, it will be noted, the attachment is concealed by the cover member when closed, except the outer leg of the clip 10 and the outer end of the set-screw 11, and will not be exposed, therefore, above the cover member or liable to be broken by objects placed thereon. The concealing of the attachment is also of material advantage in not detracting from the appearance of the receptacle or marring the outer face of the cover member when applied to highly-finished or ornamental receptacles. The cover member is thus supported in position to be opened back as indicated by dotted lines in Fig. 1 and be supported in its open position by the attachment, as will be obvious.

The parts will be of metal of sufficient strength to withstand the strains to which it will be subjected and may be of any size to adapt them to the size or capacity of the receptacles to which they are attached. Any desired number may be employed upon each receptacle and located at any desired point thereon.

Having thus described the invention, what I claim is—

1. A support for the covers of barrels and the like consisting of a clip adapted for detachable connection to the rim of the barrel and having a swinging arm movably connected therewith and adapted to be disposed within the barrel, said arm extending beneath the cover and adapted to be movably connected by its free end to the under side thereof, at a point remote from its edge.

2. A support for the covers of barrels and the like consisting of an inverted-U-shaped clip having spaced ears on the outer face of one leg and a set-screw operating through the other leg for detachable connection to the rim of a barrel, an arm hinged at one end between said spaced ears and adapted for connection by its free end to the under side of the cover member of said barrel, substantially as described.

3. A cover-support comprising an inverted-U-shaped clip adapted to fit over and be de-

tachably connected with the upper edge of a receptacle, one leg of said clip having spaced ears projecting from the outer face thereof at an intermediate point, and an arm pivotally mounted between said ears and having a plate movably connected with its free end, said plate having means for attaching it to the cover.

4. The combination with a receptacle having a cover therefor, of an inverted-U-shaped clip fitting over the edge of said receptacle with the outer leg thereof provided with a set-screw for engaging the receptacle, the inner leg having spaced ears projecting from

its outer face, an arm pivotally mounted between said ears, and a plate detachably secured to the underside of said cover and provided with depending spaced ears, the free end of said arm being movably mounted between said ears. 15

In testimony that I claim the foregoing as my own I have hereto affixed my signature in the presence of two witnesses.

RICHARD H. FESPERMAN.
